UNITED STATES PATENT OFFICE.

VLADIMIR ZAIKOWSKY, OF PETROGRAD, RUSSIA.

SHRAPNEL-SHELL.

1,290,001.

Specification of Letters Patent.

Patented Dec. 31, 1918.

Application filed March 4, 1918. Serial No. 220,358.

To all whom it may concern:

Be it known that I, VLADIMIR ZAIKOWSKY, a citizen of the Russian Republic, and resident of Petrograd, Russia, have made a certain new and useful Invention Relating to Shrapnel-Shells, of which the following is a specification, taken in connection with the accompanying drawing, which forms part of the same.

10 This invention relates particularly to the use of suitable sealing or cushioning members interposed between the shell diaphragm and the coöperating shoulder in the shell body. These members may be thin washers or collars of copper or other suitable lead composition, and if desired, these washers may be adhesively or interlocking secured to the diaphragm before it is inserted in the shell which facilitates assembly. For some purposes also, it is desirable to have these sealing washers formed with flanges extending to some extent around the diaphragm edge so as to gripingly engage the same, and if desired interlock in one or more suitable recesses which may be formed in this part of the diaphragm.

20 In the accompanying drawing showing in a somewhat diagrammatic way illustrative embodiments of this invention,

Figure 1 is a partial longitudinal section through a shrapnel shell showing this invention.

Fig. 2 is an enlarged partial section thereof; and

Fig. 3 is a similar enlarged section showing another form of construction.

As indicated in the illustrative accompanying drawings, the shell body 1 may be formed with the usual powder chamber 12 adjacent the base of the shell and with a shoulder 2 adjacent the upper end of this powder chamber with which the diaphragm 3 coöperates. This diaphragm may, of course, be secured to the ignition tube 13 in any suitable way so as to retain the powder charge in the tube and communicating chamber while the bullets or other separate projectiles 14 are packed and retained in the main shell chamber above in any suitable or usual way. The sealing member may be in the form of a washer 7 of relatively thin sheet copper or other suitable composition which is preferably soft enough to be de-

formed and forced thoroughly into the clearance spaces in this joint between the shell body and diaphragm when the parts are forced together under heavy pressure during the assembly of the shell, for example.

As shown more in detail in Fig. 2, the washer may be arranged between the shoulder 2 and the contact face 6 of the diaphragm 3 and may extend somewhat farther inward than the inner edge of this shoulder. It is also desirable in some cases to form the sealing member with a flange, such as 8, which may extend around and more or less closely embrace the adjacent diaphragm edge which may in some cases be formed with one or more holding recesses, such as 4, or with a continuous holding groove of this contour into which the edge of the holding flange 8 may be forced before the parts are assembled. It is not of course necessary, however, that such a flange should be provided in all cases and for some purposes a thin sheet or layer of copper or any other suitable or soft material may be applied to either one of these coöperating faces of the diaphragm and shoulder in any suitable way, as for instance, by the use of a coating or layer 15 formed of any suitable cementing or adhesive material such as varnish or the like. Or if desired suitable interlocking means may be used for this purpose in addition to such adhesive connection or instead thereof; and, for instance, one or more holding recesses 9 may be provided in the diaphragm which may be of dovetail contour, and in which the holding member may be secured, by forcibly pressing the sealing washer 10 into contact with the diaphragm in connection with suitable dies, if desired.

When a sealing washer or member of this general character has been preliminarily attached to the diaphragm and inserted therewith into the shell body the parts may, if desired, be powerfully forced together as by hydraulic or other presses so as to sufficiently compress and deform these soft sealing members to force them thoroughly into the coöperating recesses or clearances between these parts and in some cases to cause the relatively soft metal to flow between the diaphragm edge and shell body where the washer is of the general character shown in Fig. 3, for example. Such action of course effectively seals this joint at the upper part

of the powder chamber and prevents any possible leakage of powder into the same during transportation of the shell and also interposes a softer material between these 5 parts so as to still further minimize the possibility of sparking under the heavy pressures and impacts of firing. The firing pressures themselves may of course promote this penetration of the interposed soft sealing 10 washer material whether or not it has been forced into the joint by heavy pressure when the parts are assembled, and of course any such powerful pressure helps to hold the parts together and prevent relative rotary or 15 other movement between them when the shell is fired. The sealing and retaining member thus minimizes or prevents premature explosions from these causes so as to render the shell much more reliable and certain in operation.

This invention has been described in connection with a number of illustrative embodiments, forms, proportions, parts, materials, constructions and methods of preparation and use, to the details of which disclosure the invention is not of course to be limited, since what is claimed as new and what is desired to be secured by Letters Patent is set forth in the appended claims:

30 1. The shrapnel shell comprising a shell body formed with a powder chamber in its base and with a shoulder adjacent said powder chamber, a diaphragm coöperating with said shoulder to form the upper side of said powder chamber and an interposed sealing retaining washer formed of soft copper interposed between said shoulder and diaphragm to prevent contact between them and having a holding flange extending 40 around the adjacent diaphragm edge to grippingly engage the same and be interlocked in recesses formed in said diaphragm, said washer being adapted to be forced by the adjacent parts into the clearance spaces 45 thereof to effectively seal the joint between said parts and prevent relative motion between them.

2. The shrapnel shell comprising a shell body formed with a powder chamber in its 50 base and with a shoulder adjacent said powder chamber, a diaphragm coöperating with said shoulder to form the upper side of said powder chamber and an interposed sealing retaining washer formed of soft metal interposed between said shoulder and diaphragm to prevent contact between them and having a portion interlocked in a recess formed in said diaphragm, said washer being adapted to be forced by the adjacent parts into 55 the clearance spaces thereof to effectively seal the joint between said parts and prevent relative motion between them.

3. The shrapnel shell comprising a shell body formed with a powder chamber and 60 with a shoulder adjacent said powder chamber 65

ber, a diaphragm coöperating with said shoulder and an interposed sheet metal sealing washer interposed between said shoulder and diaphragm to prevent undesirable contact between them and having an inner edge 70 extending radially inward inside of said shoulder, said washer being forced by the adjacent parts into the clearance spaces thereof to effectively seal the joint between said parts.

4. The shrapnel shell comprising a shell body formed with a powder chamber and with a shoulder adjacent said powder chamber, a diaphragm coöperating with said shoulder and an interposed metal sealing member interposed between said shoulder and diaphragm to prevent undesirable contact between them, said member being forced by the adjacent parts into the clearance spaces thereof to effectively seal the joint 85 between said parts.

5. The shrapnel shell comprising a shell body formed with a powder chamber and with a shoulder adjacent said powder chamber, a diaphragm coöperating with said shoulder and an interposed metal sealing member interposed between said shoulder and diaphragm to prevent undesirable contact between them and connected to said diaphragm to be inserted therewith into said shell body during assembly, said member being forced by the adjacent parts into the clearance spaces thereof to effectively seal the joint between said parts.

6. The shrapnel shell comprising a shell body formed with a powder chamber and with a shoulder adjacent said powder chamber, a diaphragm coöperating with said shoulder and an interposed cushioning retaining member formed of soft metal interposed between said shoulder and diaphragm to prevent contact between them, said member being secured to said diaphragm for insertion therewith into said shell body during assembly and being forced into the clearance 100 spaces between the adjacent parts to effectively seal the joint between said parts and prevent undesirable relative motion between them.

7. The shrapnel shell comprising a shell body formed with a powder chamber and with a shoulder adjacent said powder chamber, a diaphragm coöperating with said shoulder and an interposed retaining member formed of soft metal interposed between 115 said shoulder and diaphragm to prevent contact between them, said member being forced into the clearance spaces between the adjacent parts to prevent undesirable relative motion between them.

8. The shrapnel shell comprising a shell body formed with a powder chamber and with a shoulder adjacent said powder chamber, a diaphragm coöperating with said shoulder and a thin layer of soft metal inter- 120 125 130

posed between said shoulder and diaphragm to seal the joint between them.

9. The shrapnel shell comprising a shell body formed with a powder chamber and with a shoulder adjacent said powder chamber, a diaphragm having a contact face coöoperating with said shoulder and a thin

sheet of soft cushioning material applied to one of such coöperating contact surfaces before assembly of the diaphragm within said shell body to thereupon seal the joint between said parts.

WLADIMIR ZAIKOWSKY.
